[57] CLAIM

The ornamental design for a vacuum jug or similar article, as shown and described.

DESCRIPTION

FIG. 1 is a top, front perspective view taken from one side of a vacuum jug or similar article showing my new design;

FIG. 2 is a front elevation thereof;

FIG. 3 is a top plan view thereof;

FIG. 4 is a rear elevation thereof;

FIG. 5 is a bottom plan view thereof; and

FIG. 6 is a side elevation thereof, the opposite side being the same.
